CLAIM

The ornamental design for an axial piston machine, as shown and described.

DESCRIPTION

FIG. 1 illustrates a front and side perspective view of the axial piston machine showing our new and ornamental design;

FIG. 2 illustrates a bottom plan view thereof;

FIG. 3 illustrates a rear view thereof;

FIG. 4 illustrates a left side view thereof;

FIG. 5 illustrates a front view thereof;

FIG. 6 illustrates a right side view thereof; and,

FIG. 7 illustrates a top plan view.
